Atty.

UNITED STATES PATENT OFFICE.

DONAT BROUILLARD, OF HAVERHILL, MASSACHUSETTS.

LIFTING-TACKLE.

1,377,870.

Specification of Letters Patent. Patented May 10, 1921.

Application filed June 2, 1920. Serial No. 386,055.

To all whom it may concern:

Be it known that I, DONAT BROUILLARD, a citizen of the United States, and a resident of Haverhill, county of Essex, State of 5 Massachusetts, have invented an Improvement in Lifting-Tackle, of which the following is a specification.

This invention relates to that class of lifting devices which are adapted to provide a 10 temporary handling means for barrels, boxes, bales and the like which, ordinarily, are not provided with any means whereby they may be conveniently lifted.

The objects of my invention are to provide a device of the above described character which is adapted to be readily applied to an object to be lifted, of almost any shape and size, within reasonable limits, and which will securely grasp the same, so that there 20 will be little or no danger of disengagement, and which is of simple and durable construction.

I accomplish these object by the means shown in the accompanying drawings in 25 which:

Figure 1 is a side elevation showing the application of a device, embodying my invention, to an ordinary barrel.

Fig. 2 is a perspective view showing the 30 device in position for use.

Figs. 3, 4 and 5 are detail views of one of the holding dogs.

According to my invention I provide a 35 pair of angular shaped levers or dogs, of identical construction, each being preferably formed of stiff rod iron and bent, by forging, or other means, to provide a U-shaped handle or arm portion comprising a pair of arms a , a' and a transverse connecting bar a^2 , and a similarly shaped, article-engaging, arm-portion, comprising a pair 40 of arms a^3 , a^4 , having transversely extending end portions a^5 , a^6 , which are disposed in alinement and meet midway between said arms. The handle portion a , a' , a^2 is disposed 45 in a plane approximately at right angles to the plane of the arms a^3 , a^4 and the intermediate connecting portions of the respective arms are bent to form coils or eyes a^7 , a^8 , 50 which lie within the angular space between said arms, so that the corresponding arms are tangentially disposed to the intermediate coils forming a rounded corner between them.

55 A chain b is provided, the links of which

are of a size to permit the same to run freely through the coils a^7 , a^8 , said chain being passed successively through the coils of one of the dogs and then through the coils of the other, so that the chain may be 60 passed about the object to be embraced, and the dogs may be held in operative position at opposite sides thereof. A hook c is connected to one end of the chain, the hook and links of the chain being relatively formed 65 so that the hook may be engaged in any one of the links. A ring d , of larger diameter than the internal diameter of the coils a^7 , a^8 , is connected to the opposite end of the chain from the hook, and ring e , of similar size, 70 is also connected between two links of the chain at a short distance from the hook. The ring d thus prevents the withdrawal of the chain from the dog nearest thereto and the ring e prevents the withdrawal of the 75 hook-end of the chain from the other dog beyond a certain point, so that a section of chain, of convenient length, is provided, to the end of which the hook is attached, which cannot be drawn back through the 80 adjacent dog.

In attaching the device to any object such, for example, as a barrel, the chain is passed about the barrel and, by pulling on its ends, is drawn as tight as conveniently possible, 85 and then the hook is engaged in the most convenient link, so that the chain is held in this position. Before the chain is made fast, the dogs are positioned thereon so that their handles a , a' , a^2 extend horizontally from 90 the barrel and the arms a^3 , a^4 extend above the handles and lie flat against the barrel. The dogs are also slid along on the chain, so that they are located thereon at approximately opposite points with relation to the 95 barrel.

As thus arranged, when the handles, or bars a^2 are pulled up, the upward pull on the chain will cause the end portions a^5 , a^6 , of the arms a^3 , a^4 , to be swung inward and 100 pressed against the sides of the barrel so that said end portions will act as fulcrums when lifting action is applied to the handles, and said dogs will be caused to act as levers of the 2d class on the chain, pulling 105 it outward at the points engaged, as indicated in Fig. 5. The chain will thus be drawn tightly about the barrel and firmly engaged therewith, the force of this engagement depending on the weight to be over- 110

come, as, the greater the weight, the greater will be the tension of the chain.

The pressure of the arm end portions a^5 , a^6 , against the sides of the object lifted, will also be increased in proportion to the weight supported, providing a strong frictional engagement with the barrel, in addition to the engagement of the chain.

If the device is to be principally used for 10 lifting cylindrical objects, the end portions a^5 , a^6 will preferably, be formed on a corresponding curve, as indicated in Fig. 4, to provide an increased bearing surface, as compared with the surface which would be 15 provided if they were made straight, but such variations have no essential effect on the efficiency of the device.

By providing means so that the chain will 20 always be retained in the coils a^7 , and a^8 , separation of the parts will be prevented and, by locating the ring e at a distance from the end to which the hook is attached, it will be impossible to draw the hook so closely to the dog as to make it inconvenient 25 to attach the hook to one of the chain links after the chain has been drawn tight about the object to be lifted.

The above described device may be 30 quickly and conveniently applied to an object of almost any size and shape, within reasonable limits, by the simple operation of passing the chain around it and attaching its end portions, there being no particular limitation to the length of chain which

may be employed, or to the number of dogs 35 which may be employed thereon.

I claim—

1. A lifting device for barrels and like objects, comprising a pair of angularly shaped levers each having a transverse aperture throughout substantially its entire length, intermediate its ends and a continuous chain adapted to be drawn freely through said apertures and about the object, permitting disposition of the levers 40 thereon at opposite points, said chain having means at one end adapted to be engaged with the links thereof at any point between the levers, and said levers being adapted to be fulcrumed at corresponding ends against 45 opposite sides of the object in position to draw outwardly on the chain, at the points engaged, as the opposite ends of the levers are lifted.

2. A lifting device for barrels, and like 55 objects, comprising a pair of dogs each composed of a stiff metal bar formed to provide a pair of oppositely disposed, U-shaped arms, arranged at an angle to each other, and an intermediate coil at each side, and a flexible 60 binder which is passed successively through said coils, permitting said dogs to be slid to different positions on said binder, and means to permit attachment of the end portions of the binder at different points. 65

In testimony whereof, I have signed my name to this specification.

DONAT BROUILLARD.

Correction in Letters Patent No. 1,377,870.

It is hereby certified that in Letters Patent No. 1,377,870, granted May 10, 1921, upon the application of Donat Brouillard, of Haverhill, Massachusetts, for an improvement in "Lifting-Tackle," an error appears in the printed specification requiring correction as follows: Page 2, lines 41-42, claim 1, strike out the words and comma "throughout substantially its entire length," and insert the same to follow the word "apertures" in line 44; and that the said Letters Patent should be read with this correction therein that the same may conform to the record of the case in the Patent Office.

Signed and sealed this 14th day of June, A. D., 1921.

[SEAL.]

WM. A. KINNAN,

Acting Commissioner of Patents.

Cl. 294—16.
